US00D488655S

(12) **United States Design Patent** (10) Patent No.: **US D488,655 S**
Tramontina et al. (45) Date of Patent: ** Apr. 20, 2004

(54) **DISPENSER FOR ABSORBENT PAPER PRODUCTS**

(75) Inventors: **Paul Francis Tramontina**, Alpharetta, GA (US); **David Scott Rowley**, Powder Springs, GA (US)

(73) Assignee: **Kimberly-Clark Worldwide**, Neenah, WI (US)

(**) Term: **14 Years**

(21) Appl. No.: **29/179,157**

(22) Filed: **Apr. 4, 2003**

(51) LOC (7) Cl. **20-02**

(52) U.S. Cl. **D6/518**

(58) Field of Search D6/518, 521, 522, D6/523; 206/389, 824; 221/26, 33, 282, 283; 242/570; 312/34.1, 34.4, 34.8

CLAIM

We claim the a dispenser for absorbent paper products, as shown and described.

DESCRIPTION

FIG. 1 is a partially elevated perspective view of an embodiment of the dispenser;
FIG. 2 is a front view of the dispenser shown in FIG. 1;
FIG. 3 is a left side view of the dispenser shown in FIG. 1;
FIG. 4 is a back view of the dispenser shown in FIG. 1;
FIG. 5 is a right side view of the dispenser shown in FIG. 1;
FIG. 6 is a top plan view of the dispenser shown in FIG. 1;
and,
FIG. 7 is a bottom plan view of the dispenser shown in FIG. 1.

1 Claim, 7 Drawing Sheets
